United States Patent

Des. 236,058
Patented July 29, 1975

236,058

TABLE

Friso Kramer, Amsterdam, Netherlands, assignor to
Wilkhahn, Wilkening & Hahne, Einbeckhausen, Germany

Filed May 8, 1973, Ser. No. 358,377

Claims priority, application Denmark Nov. 9, 1972

Term of patent 14 years

Int. Cl. D6—03

U.S. Cl. D6—177

FIG. 1.

FIG. 2.

FIG. 3.

FIG. 4.

FIG. 1 is a perspective view from above and at one end of a table showing my new design;

FIG. 2 is an end elevational view of the table of FIG. 1;

FIG. 3 is a front elevational view showing one of two identical ends of the table of FIG. 1; and

FIG. 4 is a bottom plan view of the table of FIG. 1. I claim:

The ornamental design for a table, as shown.
